UNITED STATES PATENT OFFICE

2,467,018

VENTILATING UNIT

Lewis W. Eggleston, Davison, Mich.

Application May 11, 1945, Serial No. 593,288

6 Claims. (Cl. 236—91)

1

This invention relates to new and useful improvements in apparatus for supplying air to and discharging air from a room.

An object of the invention is to provide a closure member for an air supply and discharge conduit which will not be opened by wind pressure.

Another object is to provide a closure member or damper which will be automatically opened by operation of a ventilating fan.

Another object is to provide means for controlling the operation of a ventilating fan.

The invention consists in the improved construction and arrangement of parts to be more fully described hereinafter and the novelty of which will be particularly pointed out and distinctly claimed.

In the accompanying drawings, to be taken as a part of this specification, there is fully and clearly illustrated a preferred embodiment of the invention, in which drawings:

Figure 1 is a view from the exterior of the ventilating unit installed in wall opening;

Fig. 2 is an enlarged detail view in section on the line 2—2 of Fig. 1, and

Fig. 3 is a view in section on the line 3—3 of Fig. 1.

Referring to the drawings by characters of reference, 1 designates the side wall of a house, such as the exterior wall of a basement room 2 preferably to be used for the storage of produce. The ventilating unit 3 is positioned in and extends through an opening 4 which may be a window opening in the wall 2. If there is space in the opening 4 around the unit 3, the space is closed by a partition 5. Felt or other sealing material 6 is used to close any cracks around the unit 3 and partition 5.

The unit 3 comprises a conduit or duct member of sheet metal which is rectangular in cross-section and has its ends open, although the exterior end 7 may be provided with a screen permitting free air flow. Inward of the exterior end 7, there is a shaft or pivot means 8 extending between and secured in apertures in the side walls 9, 10 of the conduit, midway of its height. Journalled on the shaft 8 there is a damper or valve plate 11 having equal area upper and lower portions 12, 13 respectively. On the room or inward side of the damper plate 11 there is a horizontal partition 14 dividing the conduit member into an upper air discharge or outflow passageway 15 and a lower air supply or inflow passageway 16. The plate or partition 14 terminates at its inner end edge 17 midway of the height of the conduit

2

member and closely adjacent the damper plate 11 such that it serves as a stop to limit the opening swing of the damper plate. The lower damper portion 13 swings inward into the passageway 16. The shaft 8 is sufficiently back from conduit end 7 so that the upper damper portion 12 will not swing outside of the conduit member which protects the portion 12 from the accumulation of snow or ice. The damper plate is urged to vertical conduit closing position by a counterweight 18 carried on the inside lower edge of the portion 13. The positioning of the shaft 8 out of the plane of the damper plate causes the plate by its weight due to its eccentric support to normally swing to closed position. Reverse swing of the damper plate beyond the vertical is prevented by U-shaped strips 19 of felt or the like secured to the conduit member walls. These strips also quiet or deaden the noise of damper closing. By balancing the damper plate with equal upper and lower areas, wind entering the end 7 cannot move the damper plate and the counterweight will close it even though wind is blowing. In the lower passageway 16 adjacent its room or outlet end 20, there is a draft or suction fan 21 carried by the shaft of an electric motor 22 which is mounted on a bracket 23 secured to the conduit bottom wall 24. On the inlet side of the fan 21 there is an orifice or closure plate 25 extending across the passageway 16 and having a circular opening 26 therethrough cooperable with the fan 21. The partition 14 has an upward bent or elevated portion 27 to provide fan clearance and terminates at its room end in a downward inclined portion 28 to direct discharging air from passageway 16 and fan 21 away from the inlet 29 to the passageway 15.

Mounted on the external surface of the conduit sidewall 9 there is a differential temperature control switch 30 having a casing of electric insulating material and for controlling the fan motor 22. In the casing, there are cooperable bimetal switch actuating strips 31, 32 carrying cooperable contacts 33, 34 respectively. The switch casing extends through the partition or wall 5 so that the strip 31 responds to the temperature within the room 2 or at the room end of the conduit member, while the strip 32 responds to the outdoor temperature or the temperature at the exterior end of the conduit member. Both strips move downward upon decreasing temperature, but equally for equal changes affecting both strips. If, however, the outdoor temperature decreases below the indoor temperature, then contact 34 will engage and make circuit with con-

tact 33. When the indoor temperature decreases to the outdoor temperature, then strip 31 will move contact 33 away from contact 34 and break circuit. An adjustable stop 35 cooperates with strip 32 to limit the low temperature in room 2. At a temperature of say 34° F. in the room so that produce will not freeze, the strip 32 will have contacted the stop 35 and the contacts 33 and 34 will separate. Cooperable magnet and armature members 36, 37 may be provided on the strips 31, 32 respectively so that the contacts will make and break with a snap action. The switch and motor are in series circuit. The contact 33 is connected to line by lead wire 38. The contact 34 is connected to the motor 22 by lead wire 39. The other motor terminal is connected to the other side of the line by lead wire 40.

The operation is as follows: When the temperature in the room 2 increases above outdoor temperature or vice versa, the switch 30 will close the fan motor circuit, provided the indoor temperature is not below the limit set by the stop 35. As soon as the fan 21 starts, it will create sub-atmospheric pressure in the passageway 16 on the inlet side of the fan and between the orifice plate 25 and the damper portion 13. Accordingly, the atmospheric pressure in the conduit end 7 will push the damper plate open to say the dot dash line position, Fig. 3. The pressure increase in room 2 will discharge air from the room at the higher level of the passageway 15, the upper damper portion 12 directing the discharging air away from the inlet to passageway 16. When the air supplied to the room decreases the room air temperature to the outdoor temperature, the switch contact controlling strips 31, 32 will separate, thereby breaking circuit to the fan motor 22, unless of course the stop 35 has already stopped the motor. When the motor stops, pressure will equalize on the opposite faces of the damper plate 11 and the weight 18 will swing the plate to conduit closing position. Since the plate 11 cannot be opened by wind pressure, lowering of the temperature in the room 2 below the desired degree cannot occur, thereby protecting the stored produce.

Having thus described the invention, what is claimed and desired to be secured by Letters Patent of the United States is:

1. A ventilating unit for positioning in an exterior wall opening of a room, comprising a conduit member having open ends, a freely swinging damper in said conduit member, means pivotally supporting said damper such that said damper has equal surface areas on the opposite sides of its pivot line, a partition in said conduit member having an end edge substantially parallel to said damper pivot line and terminating adjacent to said damper, said partition dividing said conduit member into longitudinal flow passageways, means tending to swing said damper into position across said conduit member and closing said passageways, and a motor driven fan in one of said passageways and operable to open said damper.

2. A ventilating unit for positioning in an exterior wall opening of a room, comprising a conduit member having open ends, a freely swinging damper in said conduit member, means pivotally supporting said damper such that said damper has equal surface areas on the opposite sides of its pivot line, a partition in said conduit member having an end edge substantially parallel to said damper pivot line and terminating adjacent to said damper, said partitions dividing said conduit member into longitudinal flow passageways,

means tending to swing said damper into position across said conduit member and closing said passageways, a motor driven fan in one of said passageways and operable to open said damper, and a differential temperature switch mounted externally on the wall of said conduit member and controlling the motor of said fan in accordance with the difference in temperatures to which the opposite ends of said conduit member are subjected.

3. A ventilating unit for positioning in an exterior wall opening of a room, comprising a conduit member having open ends, a horizontally pivoted freely swinging damper in said conduit member, means pivotally supporting said damper such that said damper has equal surface areas on the opposite sides of its pivot line, a partition in said conduit member having an end edge substantially parallel to said damper pivot line and terminating adjacent to said damper, said partition dividing said conduit member into longitudinal flow passageways, means tending to swing said damper into position across said conduit member and closing said passageways, and a motor driven suction fan in one of said passageways and operable to create a subatmospheric pressure on the damper portion closing the fan passageway thereby to open said damper.

4. A ventilating unit for positioning in an exterior wall opening of a room, comprising a conduit member, a partition in the room end of said conduit member and dividing said conduit member into an upper outflow passageway and a lower inflow passageway, a horizontally pivoted damper in said conduit member, means pivotally supporting said damper such that said damper has its pivot line dividing said damper into equal area upper and lower portions, said lower portion being swingable into said lower passageway, said partition terminating within said conduit member closely adjacent said damper and midway of the height of said conduit member, said damper lower portion being weighted thereby to urge said damper to closed position, and a motor driven fan in said lower passageway operable to create subatmospheric pressure on the passageway side of said lower damper portion so that said damper will be swung to open position upon operation of said fan.

5. A ventilating unit for positioning in an exterior wall opening of a room, comprising a conduit member, a partition in the room end of said conduit member and dividing said conduit member into an upper outflow passageway and a lower inflow passageway, a horizontally pivoted damper in said conduit member, means pivotally supporting said damper such that said damper has its pivot line dividing said damper into equal area upper and lower portions, said lower portion being swingable into said lower passageway, said partition terminating within said conduit member closely adjacent said damper and midway of the height of said conduit member, said damper lower portion being weighted thereby to urge said damper to closed position, a motor driven fan in said lower passageway operable to create subatmospheric pressure on the passageway side of said lower damper portion so that said damper will be swung to open position upon operation of said fan, and a differential temperature switch mounted externally on the wall of said conduit member and operable when the temperature at the room end of said conduit member is higher than the temperature at the exterior end of said conduit member to start said fan.

6. A ventilating unit for positioning in an exterior wall opening of a room, comprising a sheet metal conduit member, a longitudinal partition extending into said conduit member from its room end and dividing said conduit member into an upper outflow passageway and a lower inflow passageway, the room end portion of said partition being inclined downward, pivot means carried by the side walls of said conduit member midway of its height and inward from the exterior end of said conduit member, a damper supported by said pivot means and having equal area upper and lower portions so that wind pressure in the exterior end of said conduit member will not open said damper, said partition terminating at its inner end adjacent said pivot means and serving as a stop to limit opening of said damper, said damper being limited against opening movement beyond the end of said conduit member, means weighting said damper lower portion to swing said damper to closed position, a closure plate across said lower passageway and having a circular

opening therethrough, and a motor driven fan in said lower passageway cooperable with said plate opening and operable to create sub-atmospheric pressure on said lower damper portion to open said damper and draw air through said lower passageway.
